UNITED STATES PATENT OFFICE.

GABRIEL KLEM, OF GARDENTON, MANITOBA, CANADA.

SUBMARINE WIRELESS-TELEGRAPH DEVICE.

1,391,836.

Specification of Letters Patent. Patented Sept. 27, 1921.

Application filed October 25, 1920. Serial No. 419,219.

To all whom it may concern:

Be it known that I, GABRIEL KLEM, a subject of the King of Great Britain, residing at Gardenton, in the Province of Manitoba 5 and Dominion of Canada, have invented certain new and useful Improvements in Submarine Wireless-Telegraph Devices, of which the following is a specification.

The main object of this invention is to provide means whereby a submarine may signal by wireless from the bottom of the sea or at any distance under water. This is especially useful in the case of a submarine which is stranded at the bottom of the sea, 15 and which will be enabled, by means of my device to signal for help and give its position.

The above and other objects will become apparent in the description below, in which 20 characters of reference refer to like-named parts in the drawings.

Referring briefly to the drawings, Figure 1 is a side elevational view of a submarine equipped with my device.

Fig. 2 is an enlarged fragmentary view, partly in section, showing the construction of one of the floats and the arrangement of parts of my device within and upon the submarine.

Fig. 3 is an enlarged view of the various parts of the cable winding mechanism.

Referring now in detail to the drawings, the numeral 1 represents a submarine boat having a cup-like tower near either end of 35 the deck thereof. A pulley 3 is mounted in the side of said tower. Near said tower stands an upright support 4 upon which is mounted a relatively large winding drum 5 having its shaft extended and provided with 40 a bevel gear 6 lying in mesh with a horizontal bevel gear 7. The latter is rigid with a shaft 8 extending through the deck of the boat into the interior, at the latter end of which another bevel gear 9 is rigid there-

45 with. The gear 9 lies in mesh with a bevel gear 10 driven by a motor 11. Upon the motor shaft is also a second bevel gear 12 in mesh with a horizontal bevel gear 13 rigid with a shaft 14 extending upward 50 through the deck and having a bevel gear 15 rigid with its upper end. The gear 15 lies in mesh with a vertical bevel gear 16 upon the shaft of a relatively small winding drum 17.

55 A cable 18 is adapted to be wound upon the drum 5, and a cable 19 upon the drum

17. The latter near its end, is divided into two branches 19^a and 19^b. By means of a suitable eyelet and support 31 the cable 18 is attached to the bottom of a globular float 60 20 having valves 21 and 22 in the wall thereof, the valve 22 being essentially for inlet purposes and provided with a strong compression spring by which it is held in a normally closed position, while the valve 65 21, in the lower portion of the float 20, is specially adapted as an outlet. A lever 23 is adapted to engage the end of the valve stem 26 of the valve 21, said lever being pivoted at 24 and a spring 25 normally urging said lever to release said stem. The branch cable 19^a is attached to the lever 23 to operate the same as will be presently described. A lever 27 is pivoted at 30 and the stem 29 of the valve 22 is pivotally attached 70 to said lever at 28, the end of said lever being attached to the branch cable 19^b.

A staff 32 of light-weight material extends from the top of the float 20 and between said staffs on opposite ends of the 80 boat is stretched in the usual manner a wireless antenna 33. A wire 35 leads from said antenna down into the wireless room 34 of the boat, a pulley 36 being mounted upon the deck so that said wire may pass 85 thereabout in being wound or unwound.

A vertical tube 38 is mounted upon the deck adjacent the tower 2, and when the float 20 is lowered against the deck, the valve 21 lies in said tube, which is suitably 90 provided with packing or like means for forming a water-tight joint with the entered valve 21 the actuating lever 23 of which is drawn out of the way by the spring 25, as shown in Fig. 4. A pipe 39 lies in said 95 tube, and the upper end thereof is equipped with a valve 43 adapted to contact with the valve 21. The pipe 39 extends, at 40, into a pump 41 driven by a motor 42.

The operation and use of the device will 100 now be described. Assuming that the floats are idle on the deck of the submarine and filled with water and it is desired to raise them the motor 42 is driven to pump the water from the floats. Then the motor 11 105 will be driven to release the cables 18 and 19 from their respective drums, allowing the floats to rise, the cable 19 being allowed to remain slack at all times. The floats will rise to the surface of the water whence the 110 antenna 33 will take the position shown in Fig. 1, so that messages may be transmitted

in the usual manner. When it is desired to lower the floats, the motor 11 is driven in the reverse direction the cable 19 being pulled taut so as to open both valves, 5 allowing water to enter the float, which therefore descends.

I claim:

1. A device of the class described comprising floats adapted to be raised or lowered, 10 means on a submarine boat for raising or lowering said floats, means for filling or emptying said floats, one of said floats being situated at each end of said boat, staffs extending from the upper surface of said 15 floats, and an antenna stretched between said staffs.

2. A device of the class described comprising floats adapted to be raised or lowered, said floats comprising hollow globular

bodies, valves in said floats, cables attached 20 to said valves and said floats, means for winding up said cables, means for removing water from said floats, and a wireless antenna supported between said floats.

3. A device of the class described comprising floats adapted to be raised or lowered, 25 said floats comprising hollow globular bodies, valves in said floats, levers pivotally attached to said floats for operating said valves, cables attached to said valves and 30 said floats, means for winding up said cables, means for removing water from said floats, and a wireless antenna supported between said floats.

In testimony whereof I affix my signature. 35

GABRIEL KLEM.
